UNITED STATES PATENT OFFICE.

EDWIN M. CARROLL, OF PITTSFORD, MICHIGAN.

SULKY-PLOW.

SPECIFICATION forming part of Letters Patent No. 249,501, dated November 15, 1881.

Application filed October 10, 1881. (Model.)

To all whom it may concern:

Be it known that I, EDWIN M. CARROLL, of Pittsford, Hillsdale county, State of Michigan, have invented a new and useful Improvement 5 in Sulky Attachments for Plows; and I do hereby declare that the following is a full, clear, and exact description of the same, reference being had to the accompanying drawings, forming part of this specification, in which—

10 Figure 1 is a perspective view of my improved sulky attachment for plows with plow attached. Figs. 2, 3, and 4 are detail views of the same.

15 My invention relates to sulky attachments for plows, and is an improvement on my Patent No. 246,080, granted August 23, 1881; and it consists in the peculiar construction and arrangement of the parts, as hereinafter more fully set forth.

20 In the accompanying drawings, *a* represents a crank-axle having its vertical furrow-side arm longer than its land-side arm. On the horizontal portions of these arms supporting-wheels *b b*, of usual construction, are applied.

25 *c* is a sulky-frame composed of a bent metal bar. This frame is of rectangular form at its forward end, and one of its longitudinal parallel sides is clipped to the horizontal part of the crank-axle, while its other side is clipped 30 to the inner side of the guide-tongue *A*. The vertical portions *d* of the frame *c* are extended down behind the axle and pass loosely through vertically-sliding blocks *e*, which are provided, respectively, with perforated lugs. Through 35 the perforations *g* of the lugs the angular ends of parallel guide-rods *h* are passed loosely and allowed freedom to articulate up and down.

40 The guide-rods *h* extend back and are united, as shown, or in any other suitable manner.

45 Upon these guide-rods the rear portion of the plow-beam *i* is suspended by means of a rocking and rolling bar, *k*, clipped directly upon the beam *i*, and by blocks or hangers *j*, attached to the guide-rods *h*. By means of the 50 bar *k*, the ends of which are loosely fitted in the blocks *j*, and hooked eyebolts *l*, clip-plate *m*, and nuts *n*, a clamping device is formed which affords great convenience while a small plow-beam is being substituted for a larger one or a large beam for a smaller one. By turning down the nuts far enough to allow the

hooked eyes of the bolts *l* to clear the bar *k* the eyebolts can be disconnected from the bar and withdrawn from the beam, and when thus withdrawn the beam and plow will be free to be removed, so far as this clamping device is concerned. With other clamps it is necessary to remove the nuts from the bolts and to withdraw the bolts from the clip-plate before the beam and plow can be removed.

55 Forward of the clamping device *k l m*, and another similar clamping device, *e' l' n'*, and *m'*, is provided, and by means of this device like facilities for substituting a large beam for a smaller one or a small beam for a larger one are afforded. In both of these clamping devices the plates *m m'* are slotted or made in form of oblong links, and the bars *k* and *e'* are made long enough to permit the hooked eyebolts to be moved apart or together laterally 60 to suit different widths of beam; and the bar *e'* is provided with perforated ears *e²*, to which a pitman is connected.

65 The sliding blocks *e* are connected by adjustable pitmen *t r s u* to a double-crank shaft, *o*, which has one of its cranks, *p*, set just opposite the other, *q*, as shown.

70 The pitmen consist, respectively, of a strap having holes *g'* and a rod, the latter being attached by its lower bent end to a lug of a block, *e*, and hooked by its upper hooked end into one or the other of the holes in one of the straps *t* or *u*. The double-crank shaft is pivoted to the frame *c* and tongue *A* near the rear end thereof. The cranks *p* and *q* lie in 75 the same plane, and one extends back and the other forward. In some instances the crank-shaft will be pivoted wholly to the frame *c* and have no connection directly with the tongue *A*. One end of the crank-shaft *o* is connected 80 by an upturned extension, *v*, thereon, and a rod, *w*, to a hand-lever, *x*, said lever being, as usual, provided with a spring-pawl, *y*, which engages in a curved rack, *a'*. By means of the cranks *p* and *q* of the shaft *o* the sliding blocks will 85 be moved in opposite directions upon the guiding extensions *d* of frame *c* when the lever *x* is moved forward or backward, and, owing to the sliding blocks moving in opposite directions, the guide-rods will be caused 90 to rock the bar *k*, with the plow-beam, to the right or left, accordingly as the lever is moved,

and thus the plow will be winged or leveled to suit the elevations or depressions of the ground; and by having the guide-rods free to articulate in the holes *g* in the lugs of the blocks *e* the wheels *b* of the sulky are free to rise and fall in passing over obstructions without affecting the plow or its connections; or, in other words, the plowshare will remain at its adjusted plowing depth while the wheels *b* are rising or falling.

Forward of the double-crank shaft *o* a single crank, *b*, is pivoted to the sulky-frame, near the rear end thereof. To this shaft the plow-beam is connected by means of a laterally-adjustable pitman, *c' d'*, and the clamping device *e'*, *l'*, *m'*, and *n'*. The crank-shaft *b* is connected to an upturned extension, *i'*, on one of its ends, and by a rod, *j'*, to a lever, *k'*, which is provided, as usual, with a spring, *l''*, which engages with a curved rack, *m''*.

By means of the crank *b* and its connections the plow can be raised bodily out of the furrow or lowered, as may be desired; and by means of the clamping devices and the sliding pitman-strap the plow can be adjusted either to the right or left, as may be desired. While raising or lowering the plow the guide-rods *h* articulate in the holes of the lugs of the blocks *e*, while the sliding blocks *j* slide upon the rods, and thus do not interfere with the movement of the plow. The sliding blocks *j* do not require to slide while the plow is being winged or leveled, and therefore my invention for effecting the winging or leveling of the plow could as well be carried into effect by attaching the bar *k* to other hangers or supports for its ends. These blocks *j* might have their upper edges similar in form to their lower edges, and in the portions above the rods *h* holes *h* might be formed for the reception of the ends of the bar *k*, accordingly as the height of the plow-standard would require, and in such case the pitmen *t r* and *s u* would not require to be lengthened or shortened to suit the plow. I however prefer the adjustable pitmen.

Adjustable chains *n*² are suitably secured to the front end of the plow-beam and to the lower horizontal parts of the axle, and by these chains the sulky is drawn and kept in line with the plow.

Power is applied directly to the plow-beam, and an adjustable neck-yoke is applied to the outer end of the sulky-tongue in the usual manner.

What I claim as my invention, and desire to secure by Letters Patent, is—

1. The double-crank shaft *o*, having opposing cranks, and the laterally-rocking bar *k*, the latter firmly clamped to the beam, in combination with the vertically-sliding blocks *e*, loosely fitted to the parts *d* of the frame *c*, and articulating guide-rods *h*, provided with supports for the ends of the rocking bar *k*, substantially as and for the purpose described. 60

2. The combination of the double-crank shaft *o*, having opposing cranks, connecting pitmen, sliding blocks *e*, and frame *c d*, substantially as described. 65

3. The combination of the crank-shaft *b'*, pitman *d'*, clamping device *e' l' m'*, articulating guide-rods *h*, bar *k*, and longitudinally-sliding blocks *j*, substantially as and for the purpose described. 70

4. In combination with the beam *i*, the clamping device consisting of the bar *e'*, provided with perforated ears *e²*, the screw-threaded hooked eyebolts *l'*, link *m'*, and nuts *n'*, substantially as described. 75

5. The clamp *l m* and plow-beam *i*, in combination with the laterally-rocking bar *k*, blocks *j*, and guide-rods *h*, substantially as and for the purpose described. 80

6. The combination of the bar *k*, having both a rolling and rocking motion, beam *i*, articulating guide-rods *h*, longitudinally-sliding blocks *j*, vertically-sliding blocks *e*, frame *c d*, and crank-shaft *o*, having opposing cranks, substantially as described. 85

7. The two loosely-fitted sliding blocks *e*, connected to the plow-beam and frame *c d*, and to the double-crank shaft by suitable intermediate means, and operated by a lever from the driver's seat, whereby one sliding block is raised and the other lowered simultaneously, and the plow thereby winged or leveled, substantially as described. 90
